UNITED STATES PATENT OFFICE.

LEONARD ALBERT HINDLEY, HAROLD DOUGLAS HINDLEY, AND WILLIAM STANFORD, OF BOURTON, ENGLAND; SAID STANFORD ASSIGNOR TO SAID LEONARD ALBERT HINDLEY AND SAID HAROLD DOUGLAS HINDLEY.

MANUFACTURE OF HORSESHOES.

1,269,813.

Specification of Letters Patent. Patented June 18, 1918.

Application filed April 27, 1917. Serial No. 164,834.

To all whom it may concern:

Be it known that we, LEONARD ALBERT HINDLEY, HAROLD DOUGLAS HINDLEY, and WILLIAM STANFORD, subjects of the King of England, all residing in Bourton, Dorsetshire, England, have invented certain new and useful Improvements in the Manufacture of Horseshoes, of which the following is a specification.

10 This invention relates to the manufacture of horse-shoes and provides an improved process therefor, together with means for carrying out the said process. The means provided by the present invention take the 15 form of an improved construction of machine of the kind in which the stock is "turned" by being bent around a core-pattern by means of a wiper.

It has heretofore been proposed to manufacture horseshoes by punching or rolling processes which formed in the material holes that were parallel to one another, and subsequently to cut the material thus pierced into lengths which were then bent to the 25 usual shape. It is an object of the present invention to provide a process for the rapid and economical production of horseshoes, preferably in a single heating, from plain bar stock, and further, if desired, a process 30 by which the holes shall have the requisite inclination to one another.

The present invention, therefore, provides a process for making horseshoes consisting in (a) drilling the stock cold with 35 round holes for nail-holes prior to being "turned" (b) subsequently "turning" the stock whereby the round holes are made approximately oval and (c) drifting the holes to their final shape after the stock has been 40 "turned."

The term "turned" above and herein employed is used to denote the operation of bending the stock to the curved shape of the horseshoe.

45 For carrying out the process according to our invention, a machine will now be described, whereby the process may be clearly understood.

In the accompanying drawings:—

50 Figure 1 is a side elevation of a machine for carrying out the process referred to above;

Fig. 2 is a plan of the machine, and

Fig. 3 is an elevation of the machine viewed from the right of Figs. 1 and 2. 55

The same letters indicate the same parts throughout the drawings.

The machine is carried on a table A which may be of steel, and rigidly secured to the table is a core A¹ whose periphery is shaped to the form the interior of the finished horseshoe is desired to take. Extending up through the circular portion of the core, and approximately concentric with said portion, is a vertical spindle B. This spindle can 60 slide up and down but does not rotate, and fast upon it is a plate B¹. At the top of the spindle is another plate B² whose periphery is provided with steps set at different angles for the purpose hereinafter 65 described. Mounted to pivot in any convenient manner upon the spindle B is a lever C. This lever lies immediately beneath the plate B¹, has a heel C¹, and carries on its underside a roller C². The heel 70 C¹ is so placed that when a horseshoe, such as is indicated at D, is in place around the core A¹ and the lever C is in the position shown in Fig. 2; the heel will lie over that end of the horseshoe remote from the 75 roller C² and the roller will bear against the opposite end of the horseshoe.

An adjustable stop E is provided for the starting end of the shoe and a file-faced clamping-finger F is pivoted at F¹ near to 80 the stop. The clamping-finger is controlled by a spring F² which always tends to move it away from the shoe, and a locking-lever G is provided, having an eccentric G¹ whereby the finger can be forcibly pressed 85 against the shoe.

To move the spindle B endwise, a lever H, pivoted at H¹, extends through a slot B³ in the spindle and can be pressed downward against a spring-control when desired; 90 the spring-control is not shown in the drawing.

Pivoted to the lever H at J¹ is a bar J which carries two plungers J². These plungers extend through the table A and lie 95 beneath the position occupied by a shoe when in position around the core.

A shoe is formed as follows:—The stock is cut to dead length and drilled cold for the nail-holes at the correct angles by means 100 of jigs. It is then heated, and while hot 105

is placed at the side of the core A¹ with its end against the stop E. The lever G is then pulled over and thus immediately clamps the stock against the side of the core. A tap 5 with a hammer drives the part to the rear of the piece F against the core. Alternatively, the piece F may be situated sufficiently to the left (as viewed in Fig. 2) to effect this itself. When the stock is inserted 10 in the machine the lever or wiper-bar C lies over on the opposite side of the core from that occupied by it in Fig. 2 so that the roller C² will lie behind the stock as viewed in Fig. 2. The wiper-bar is now swung 15 around clockwise to bring it to the position shown in Fig. 2. By this movement the stock is "turned" by the roller pressing against it and bending it around the core A¹. When this movement is completed, the heel 20 C¹ of the wiper-bar projects over the starting end of the shoe and the roller bears against the finishing end and holds it firmly against the core. The lever H is then depressed whereby the wiper-bar is made to 25 press upon the shoe-ends so as to hold the shoe in position while the holes are punched. The holes, which were circular when drilled, are now oval owing to the "turning" movement, and the holes are now 30 drifted by placing one or more drifts against the steps provided on the periphery of the plate B². These steps are set at such an angle as to engage the upper part of the drift and bring it to the correct angle at 35 which the holes are to be struck. This having been done, a clip is formed on the shoe at D¹ by hammering this portion and the plate B¹ is provided with a jaw clearly shown in Fig. 2, which can accommodate the 40 tool for striking down the metal prior to forming the clip by hammering the metal so struck down against the side face of the table A. All these operations are carried out during the single heat as they can each 45 be quickly effected and the shoe therefore has no time to cool before it is finished.

As soon as these operations are completed, the lever H, which may be held down by a rack or other suitable means, is released so

that it rises under its spring-control and 50 thus releases the shoe; the lever G is swung back to release the holding finger F, and if the shoe sticks on the core, the lever H may be slightly raised so that the plungers J² 55 push it upward off the core.

The adjustability of the stop E enables 60 shoes of slightly longer length than is provided for by the core to be made if desired, while nevertheless insuring that the stock when wiped shall be correctly placed for 65 the drifting of the holes and the forming of the clip; the finger F further operates to insure that the stock shall not be drawn away from the stop E during the wiping operation. 65

A prominent advantage in the process provided by this invention is having the holes properly inclined to the face of the shoe to give the right direction to the nails, and it will be readily seen that such inclination of the holes cannot be obtained if they are punched simultaneously with one another by a multiple punch, as has heretofore 70 been proposed.

What we claim as our invention and desire to secure by Letters Patent is:— 75

1. In a process for making horseshoes, the steps consisting in, drilling round nail-holes in the cold stock, heating the stock, "turning" the same whereby the round holes 80 are made approximately oval and in the same heat drifting the holes to their final shape, substantially as set forth.

2. In a process for making horseshoes, the following steps consisting in, forming in the 85 stock while cold nail-holes the throughway of which is inclined to the face of the stock at approximately the angles required in the finished article, heating the stock, "turning" the stock, and drifting the nail-holes formed 90 while the stock was cold to their final shape, substantially as set forth.

In testimony whereof we have signed our names to this specification.

LEONARD ALBERT HINDLEY.
HAROLD DOUGLAS HINDLEY.
WILLIAM STANFORD.
